DESIGN FOR A TEXTILE FABRIC OR THE LIKE

Everett E. Sherwin, Mamaroneck, N. Y.

Application June 6, 1933. Serial No. 48,293

Term of patent 3½ years

To all whom it may concern:

Be it known that I, EVERETT E. SHERWIN, a citizen of the United States and resident of Greenhaven, Mamaroneck, in the county of Westchester and State of New York, have invented a new, original, and ornamental Design for a Textile Fabric or the like, of which the following is a specification, reference being had to the accompanying drawing, forming a part thereof, in which the one figure is a plan view.

The textile fabric is particularly adapted to be used for table cloths, bridge cloths, napkins and scarfs.

I claim:

The ornamental design for a textile fabric or the like substantially as shown and described.

Dated May 29, 1933.
